CLAIM

The ornamental design for an outer shell of an item carrier, as shown and described.

DESCRIPTION

FIG. 1 is a front, top, right side isometric view of an outer shell of an item carrier showing the design;

FIG. 2 is a bottom, back, left side isometric view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.
